NURSING BOTTLE

Heath Cortland Reese and Charles Newton Reese,
Wilmette, Ill., assignors to Barnett & Truman,
a firm composed of Otto R. Barnett and Per-
cival H. Truman, Chicago, Ill.

Application July 13, 1933, Serial No. 680,214

7 Claims. (Cl. 215—11)

This invention relates to improvements in nursing bottles and has for its principal object the provision of improved means for admitting air into a nursing bottle so as to maintain substantially atmospheric pressure therein at all times during the withdrawal of the liquid contents from the bottle.

A more specific object is to provide a nursing bottle having an air vent port therein and a valve 10 for opening and closing said port in response to the withdrawal of liquid from the bottle, both said vent port and said valve being so formed as to facilitate thorough cleansing of the parts.

Another specific object is to provide a nursing bottle with an air vent port and a resilient valve therefor which may be readily and conveniently inserted in or removed from said port and which when in its applied position will provide an efficient seal against leaking of milk or other liquid 20 from the bottle.

Another object is to provide a vent valve for a nursing bottle which will operate automatically to admit air into the bottle during the withdrawal of liquid therefrom and thereby avoid collapsing of the nipple and which may be also manually operated to permit controlled amounts of liquid to flow by gravity through the nipple, thereby providing a simple and efficient means for feeding infants who are too weak or disinclined to withdraw the liquid from the bottle.

Further objects will be apparent from the detailed description of the embodiment of the invention shown in the accompanying drawing wherein Fig. 1 is a view in perspective of a nursing bottle embodying the improvements of the present invention.

Fig. 2 is a longitudinal section through the nursing bottle shown in Fig. 1.

Fig. 3 is a fragmentary sectional view of the bottle adjacent the air vent port and illustrating a pressure actuated valve for closing said port; said valve being illustrated in its open position in this figure; and

Fig. 4 is a view in perspective of the valve structure employed herein for opening and closing the air vent port of the nursing bottle.

The invention contemplates the use of various forms of bottles or other containers provided with or adapted to receive nipples or other devices for withdrawing liquid from such bottle or container.

The present embodiment includes a bottle 10 formed with a neck portion 11 having a discharge opening 12 and provided also with an external rib 13 for retaining thereon a suitable nipple 14.

55 The particular form of nipple is not important

insofar as the present invention is concerned. Obviously, any suitable form of nipple may be used. The body portion of the bottle is preferably, but not necessarily, formed with one or more flat sides 15 and is provided also with an air vent opening 16. This opening is relatively large so as to facilitate thorough cleansing and sterilizing of the bottle. Said opening is preferably of such size as to permit the insertion of a brush or other cleaning implement when washing the bottle.

The vent opening 16 is closed by a valve 17 adapted to seat against the inner surface of the bottle. The valve is made of resilient material, preferably soft rubber, so that it may be readily inserted through the opening 16 to its operative position and so that it will conform to the contour of the inner surface of the bottle. In the present instance the valve is formed to present a substantially cone shaped configuration in cross section. The valve is made of minimum thick-

ness at 17^a its central annular portion and increases in thickness toward its edge and terminates in an upstanding rib 18 which extends around the edge portion of the valve and seats against the inner wall of the bottle. This construction provides the desired resilience to permit the valve to be easily applied or removed from the bottle and at the same time insures proper seating of the rib 18 against the inner face of the bottle. The decreased thickness of the valve at 10 17^a also decreases the resistance in unseating the rib portion 18 of the valve and consequently renders the valve more 15 sensitive to an air pressure differential between the inside and outside of the bottle. The 20 valve, it will be seen from the drawing, is somewhat larger than the vent opening 16 in the bottle so that the valve, even though it be arranged eccentric to the axis of the opening, will 25 completely close said opening. 19 designates the 30 stem portion of the valve. It is preferably made of resilient material and is formed integrally with the valve. A cup-shaped member 20, which is 35 also preferably resilient, is formed integrally with the upper end of the valve stem, and supports 40 the valve in its proper position. The said cup-shaped supporting member 20 is adapted to conform to the outer wall of the bottle 10 which, in 45 the present instance, is flat. An air passage 21 is formed in the supporting cup member 20 so as 50 to permit the external air to pass through the opening 16 into the interior of the bottle when the valve 17 or any part thereof is moved away from the inner wall of the bottle.

The upper edge of the rib 18 of the valve is so 55

positioned relative to the lower edge of the cup-shaped member 20 that these parts are spread apart slightly when the valve is in its normal applied position. Consequently, the resilience of the valve structure as a whole holds the rib 18 of the valve against the inner wall of the bottle to prevent leakage at this point when the bottle is so positioned that the level of the milk or other liquid contained therein is above or in contact with the valve.

In operation, a resilient valve is inserted through the vent opening so as to seat against the inner wall of the bottle as indicated in Fig. 2 of the drawing. The bottle is then sterilized and filled with the desired liquid and the nipple is applied. The valve 17 being held in its closed position by the resilience of the material of the valve and associated parts will prevent any of the liquid leaking through the valve or through the nipple.

During the withdrawal of liquid from the bottle, for example by a nursing infant, the difference in the internal and external air pressure will be sufficient to cause the valve to yield and thereby automatically admit sufficient air into the bottle to compensate for the amount of liquid withdrawn. The air pressure within the bottle is therefore maintained at a point substantially equal to the external pressure at all times during the feeding of the infant. This condition insures a free flowing of the liquid through the nipple and avoids any collapse of the nipple during the feeding of the infant.

In some instances, for example when the infant is too weak or disinclined to withdraw the milk or other liquid from the bottle, the milk can be discharged from the bottle in proper quantities to suit the feeding of the infant, the said discharge being controlled by manual operation of the valve. By pressing downwardly on the upper portion of the cup-shaped support 20, the valve 17 may be moved away from the inner surface of the bottle as indicated in Fig. 3 of the drawing. In this event the air at atmospheric pressure is admitted to the bottle and thereby permits the fluid in the bottle to discharge freely from the usual apertures in the nipple. As soon as the valve is permitted to close the discharge of liquid is interrupted. It will be seen therefore that this manual control of the discharge of liquid from the bottle can be regulated in accordance with the amount of liquid required by the infant.

When it is desired to wash the bottle the nipple 14 and the vent valve structure are removed from the bottle. The vent valve structure being a unitary construction of flexible material can be readily washed and thoroughly sterilized before it is again applied to the bottle. If desired, the valve and bottle may be thoroughly sterilized after the valve has been inserted in the opening 16 of the bottle.

Although we have herein shown and described what we now consider a preferred form of valve structure and nursing bottle, it will be apparent that the constructions illustrated may be varied or modified without departure from the spirit of this invention. It will be understood therefore that the present invention contemplates all such changes and modifications that come within the scope of the claims appended hereto.

We claim:

1. In combination with a nursing bottle having a discharge opening and an air vent in the wall of the bottle, a unitary valve structure comprising a flexible valve of larger diameter than said vent opening, but adapted to be readily inserted and

withdrawn therethrough, said valve being adapted to seat on the inner surface of said bottle and to open when the air pressure within the bottle becomes substantially less than atmospheric pressure, a valve stem adapted to project loosely through said vent leaving space therein for the passage of air therethrough, and a resilient supporting member adapted to engage the outer surface of the bottle normally to hold said valve in a closed position but yielding to slight manual pressure toward said valve to unseat the same.

2. In combination with a nursing bottle having a discharge opening and an air vent opening in the wall of the bottle, a unitary valve structure comprising a flexible cup shaped valve of larger diameter than the vent opening but adapted to be readily inserted and withdrawn therethrough, the outer edge of the said cup shaped valve being adapted to seat on the inner surface of the bottle normally to close the vent opening and to open responsive to an increased proportion of outside to inside air pressure, a valve stem adapted to project loosely through said vent leaving space therein for the passage of air therethrough, and a resilient supporting member adapted to engage the outer surface of the bottle normally to hold said valve in a closed position but yielding to slight manual pressure toward said valve to unseat the same.

3. In combination with a nursing bottle having a discharge opening and an air vent opening in the wall of the bottle, a unitary valve structure comprising a flexible cup shaped valve of larger diameter than the vent opening but adapted to be readily inserted and withdrawn therethrough, the outer edge of the said cup shaped valve being adapted to seat on the inner surface of the bottle to close the vent opening and to open the same responsive to an increased portion of outside to inside air pressure, a valve stem adapted to project loosely through said vent, leaving space therein for the passage of air therethrough, and a cup shaped supporting member adapted to engage the outer surface of the bottle normally to hold said valve in a closed position, but yielding to slight manual pressure toward said valve to unseat the same, said supporting member being formed with an opening to provide an air passage to said air vent.

4. In combination with a nursing bottle having a discharge opening and an air vent opening in the wall of the bottle, a one piece valve structure formed of resilient material, said valve structure comprising a valve of larger diameter than the vent opening but adapted to be readily inserted and withdrawn therethrough, the outer portion of said valve being adapted to seat on the inner surface of the bottle and the central annular portion of said valve being of decreased thickness to facilitate the unseating of the valve when the air pressure within the bottle becomes substantially less than atmospheric pressure, a valve stem adapted to project loosely through said vent opening to leave an air passage therein, and a resilient supporting member adapted to engage the outer surface of the bottle normally to hold said valve in a closed position but yielding to slight manual pressure toward said valve to unseat the same, said supporting member being formed with an opening to provide an air passage to said air vent.

5. In combination with a nursing bottle having a discharge opening and an air vent opening in the wall of a bottle, a one piece valve structure formed of resilient material, said valve structure

- comprising a cup shaped valve of larger diameter than the vent opening but adapted to be readily inserted and withdrawn therethrough, the outer edges of said cup shaped valve being adapted to seat on the inner surface of the bottle normally to close the vent opening but adapted to open the same responsive to an increased proportion of outside to inside air pressure, and the central annular portion of said cup shaped valve being of decreased thickness, a valve stem projecting loosely through said vent opening to leave an air passage therethrough, and a resilient supporting member adapted to engage the outer surface of the bottle normally to hold said valve in a closed position, but yielding to slight manual pressure toward said valve to unseat the same, said supporting member being formed with an opening to provide an air passage to said vent. 5
6. In combination with a nursing bottle having a discharge opening and an air vent opening in the wall of the bottle, a one piece valve structure formed of resilient material, said valve structure comprising a cup shaped valve of larger diameter than the vent opening but adapted to be readily inserted and withdrawn therethrough, the outer edges of said cup shaped valve being adapted to seat on the inner surface of the bottle to close the vent opening and to open responsive to an increased proportion of outside to inside air pressure, and the central annular portion of said cup shaped valve being of decreased thickness, a valve 10
- 10 stem projecting loosely through said vent opening to leave an air passage therethrough, and a cup shaped supporting member adapted to engage the outer surface of a bottle normally to hold said valve in a closed position but yielding to slight manual pressure toward said valve to unseat the same, said supporting member being formed with an opening to provide an air passage to said vent. 15
7. A one piece valve formed of rubber and adapted to control the passage of air through an air vent in a container to maintain substantially atmospheric pressure in said container as the contents are withdrawn therefrom, said valve structure comprising a cup shaped valve of larger 10 diameter than the air vent but adapted to be readily inserted and withdrawn therethrough, the outer edges of said cup shaped valve member being adapted to seat on the inner surface of the container normally to close the air vent but to 20 open the same when the air pressure within the container falls substantially below atmospheric pressure, a valve stem adapted to project loosely through said air vent opening to leave an air passage therethrough, and a cup shaped supporting member adapted to engage the outer surface of the container normally to hold said valve in a closed position but yielding to slight manual pressure toward said valve to unseat the same. 25
